Filed May 17, 1962, Ser. No. 195,539

8 Claims. (Cl. 204—228)

This invention relates to an improved method and apparatus for producing barretters of the type employed for power measurements at microwave frequencies.

Barretters of the type with which this invention is concerned are extremely thin wires of such small size that they are hardly visible to the naked eye. They have the electrical characteristics that their resistance changes with temperature and they are utilized by placing them in a microwave transmission line such as a hollow waveguide or a coaxial transmission line, and by connecting them as one element of a suitable bridge circuit. Electromagnetic energy absorbed by the barretter causes its resistance to change, thus changing the condition of balance or unbalance of the bridge circuit. The change in resistance of the barretter can be used to determine the amount of electromagnetic energy absorbed by the barretter by any one of several different methods. Detailed descriptions of barretters and their operation are outlined in sections 3.23 and 3.24 of "Techniques of Microwave Measurements," by Montgomery, McGraw-Hill Book Company, Inc., New York, New York, copyright 1947.

The power sensing element of the more commonly used sensitive barretters consists of a short length of extremely fine platinum wire. The diameter of the platinum wire is in the order of 30 to 60 microinches. Since wire of this size is impossible to draw directly and would be very difficult to handle if it were, it is necessary to use the Wollaston process to obtain wire of this extremely small size. Wollaston process platinum wire is made by drawing the platinum inside a silver jacket or coating. By properly proportioning the diameters of the platinum rod and silver jacket at the start of the forming and drawing process, the final diameter of the platinum core can be controlled to rather close limits. The silver jacket in addition to providing a means for drawing the platinum to such small diameters also provides the additional strength and body necessary to handle the wire during the initial manufacturing steps, and also provides a convenient means for achieving the exact resistance value of the barretter wire. This resistance value is obtained by removing the silver jacket over a portion of the length of the Wollaston wire to leave exposed the higher resistance platinum core. Because of the very fine nature of the Wollaston wire it is difficult to work with and breakage of the wire during the etching process to remove the silver jacket and during the assembly of the wire into a suitable holder can be quite high. Additionally, the desired control of the etching process may be difficult. Because the present drawing processes do not provide precise control of the Wollaston wire diameter, it is not possible to etch the wire to a certain fixed physical length and be assured of obtaining the desired resistance value. Control of the etching process is important because the finely etched wire must have specific electrical and physical characteristics. It is very important that all of the silver be removed from the platinum core throughout the etched area because any silver particles not removed from the platinum core may alloy with the platinum at high temperatures and change the resistance value of the etched wire.

One method for producing barretters is disclosed in U.S. Patent 2,468,796, assigned to the applicant's assignee. This method has been used successfully but suffers from the disadvantage that it requires highly skilled personnel,

2

and the useful output yield of that method is not always as high as desirable because it is difficult to obtain uniformity of etching on a production basis and because the silver particles cannot be completely and uniformly removed from the etched portion of the platinum wire by this method.

It therefore is an object of this invention to provide an improved apparatus and method for producing barretters that have improved and consistently repeatable electrical characteristics.

It is another object of this invention to provide an improved method for making barretters that permits closer control of the etching process resulting in more uniform and consistent barretters.

It is a further object of this invention to provide a semi-automatic apparatus for etching barretter wires, wherein the semi-automatic feature affords precise control over the etching process.

It is another object of this invention to provide means for accurately controlling the area to be etched and the rate of etching of a Wollaston wire, which together with automatic control of the etching current, produces a greater yield of barretter wires of superior characteristics.

In accordance with the present invention, a Wollaston wire to be electrolytically etched is supported on an assembly fixture between axially aligned supporting members. The ends of the supporting members and the ends of the Wollaston wire are masked by enclosing them within a suitable material that is resistant to electrolytic etching. The masking material is applied so as to leave exposed a fixed central portion of the wire. A droplet of a suitable electrolyte is brought into contact with the central unmasked portion of the wire so as to completely surround the wire. The wire is connected as the unknown resistance element in an A.C. resistance measuring bridge circuit, and a D.C. electrolytic etching current circuit is established between the wire and the droplet of electrolyte. The etching current circuit includes an electrically controllable current interrupting element that is controlled by the condition of balance or unbalance of the bridge circuit. That is, the current interrupting means maintains the etching current circuit in a current conducting condition when the bridge is unbalanced and breaks the circuit when the bridge is in a balanced condition. During the initial stage of etching of the Wollaston wire, the unmasked central portion of the silver coating is removed at a relatively rapid rate, but the masked portion of the wire has been selected so that the desired resistance value has not yet been obtained. The etching then proceeds at a slower rate to remove the ends of the silver coating under the masking material, and to thoroughly "clean up" the etched central portion of the wire. This etching continues at a slower rate until the desired resistance value is reached. When the Wollaston wire has been etched so as to achieve its desired resistance value, the bridge will be in a balanced condition and the current interrupting means becomes deenergized and opens the etching current circuit, thereby automatically terminating the etching process.

The present invention will be described by referring to the accompanying drawings wherein,

FIG. 1 is a perspective view of an assembly fixture on which a barretter is made, and is used in explaining the method of assembling the barretters;

FIG. 2 is a simplified sketch, partly in schematic form, illustrating the electrical equipment and control apparatus, and the masking material used in the electrolytic etching of the silver coating from a portion of a Wollaston wire;

FIG. 3 is an illustrative sketch of the view of a partially assembled barretter as seen through a microscope

and is used in explaining the manner in which the masking material is applied to the Wollaston wire; and

FIG. 4 is a simplified illustration of the etched resistance wire prior to encapsulation.

Referring now in detail to FIGURE 1, the assembly fixture 10 that is used in assembling the barretters is composed of upstanding end posts 11 and 12, both supported on a base 13. End posts 11 and 12 are electrically insulated from base 13, and from each other, and for this purpose base 13 may be made of a non-conductive material. Extending transversely through end members 11 and 12 are respective axially-movable conductive positioning members 16 and 17, both of which are slideable through transverse holes in the respective end members 11 and 12. Positioning member 16 has an enlarged collar 18 at its left end for fixing the position of member 16 with respect to end post 11. Positioning members 16 and 17 are bored at their adjacent inner ends to receive the end members 20 and 21 to which are secured the power-absorbing resistance wire 22, a Wollaston wire as previously described. End members 20 and 21 have respective closing plugs 24 and 25 thereon which will form the ends of the finally-encapsulated barretter. The closing plugs 24 and 25 may be in the form of collars of greater diameter that are machined as integral parts of end members 20 and 21, or may be separate annular plugs that slip over the end members 20 and 21 and may be fastened to the end members some time during the assembly process. Positioning members 16 and 17 may be secured against axial movement with respect to end posts 11 and 12 by means of respective set screws 28 and 29.

The means for introducing a droplet of an electrolyte into contact with Wollaston wire 22 is illustrated by the apparatus 30 which is comprised of tool holder 31 to which is secured the tool 32 that has a small reservoir 33 at its end for supporting a droplet 34 of electrolyte, which may be a ten percent solution of potassium cyanide. Tool holder 31 is vertically movable by rotation about an axial pin 45 that is secured between vertical posts 46 and 47. Tool holder 31 may be clamped in position by turning a handle 48 that turns screw 49 to bring posts 46 and 47 tightly against tool holder 31. Tool holder 31 may be moved longitudinally parallel to the wire 22 by means of enlarged holes 51 and 52 through which pass the clamping screws 55 and 56. The length of tool 32 may be adjusted by suitable means not illustrated. As now may be understood, droplet 34 of the electrolyte is positionable both vertically and longitudinally to bring it into contact with the portion of the resistance wire 22 to be electrolytically etched.

To accomplish the electrolytic etching of the silver jacket or coating from the Wollaston wire 22 in accordance with this invention, a direct current electrolytic etching current is passed through the reservoir 33, through droplet 34 of the electrolyte, to Wollaston wire 22 in such a direction as to remove or deplate the silver jacket from the Wollaston wire, thus exposing the platinum core of the wire. The electrical circuitry for accomplishing this electrolytic etching in accordance with this invention is illustrated in simplified schematic form in FIG. 2. The positioning members 16 and 17 with the end members 20, 21 and Wollaston wire 22 conductively connected therebetween are connected as one leg of an A.C. bridge circuit 81, which may be of any of the types commonly used in the art. An oscillator 82 is connected across the bridge circuit 81, and an A.C. amplifier 60 is connected to one point of the bridge in a manner to be energized by the bridge circuit when it is in its unbalanced condition. Substantially no input signal flows to amplifier 60 when the bridge is balanced. The output of amplifier 60 is coupled to etching control circuit 83 which when energized by the output of amplifier 60 maintains a closed etching current conduction path from a D.C. source of etching current E_{dc} through posi-

tioning member 17, end member 21, Wollaston wire 22, droplet 34 of the electrolyte, and thence through the reservoir 33, tool holder 31, and through the etching control circuit 83 back to the other terminal of source E_{dc} . Etching control circuit 83 may be comprised of a relay actuated switch, for example. When bridge 81 is in the balanced condition, there is no output from amplifier 60 and etching control circuit 83 operates to open the electrolytic etching current path, thus terminating the etching process. The use of an A.C. resistance measuring bridge circuit 81 and A.C. amplifier 60 provides isolation from the D.C. etching current circuit since amplifier 60 will block D.C. signals, thus making the operation of etching control circuit 83 independent of the etching current flowing and rendering its operation dependent entirely upon the resistance of the etched Wollaston wire 22 as monitored by bridge circuit 81.

The method of producing barretters in accordance with the present invention is carried out in the following manner. Referring to FIG. 1, end members 20 and 21 are positioned in the respective ends of positioning members 16 and 17, and positioning member 16 is moved inwardly until collar 18 is in intimate contact with end post 11. Set screw 28 then is turned in to secure positioning member 16. Positioning member 17 is positioned a fixed axial distance from the end of member 16 by means of some suitable gage tool and is then secured in position by set screw 29. Set screw 28 is backed off, positioning means 16 partially withdrawn, and a thin shim 62 of the order of .005 inch thick is placed between collar 18 and end post 11 for reasons that will become apparent from the later description. Positioning member 16 then is moved inwardly to its limit fixed by collar 18 and shim 62, and is secured by set screw 28. An encapsulating sleeve 65, which may be polystyrene or some other suitable low loss dielectric material, then is slipped over the end of end member 20 and positioning member 16 and is moved to the left away from the space between end members 20 and 21. Resistance wire 22, a Wollaston wire, then is secured to the adjacent ends of end members 20 and 21 by soldering. Resistance wire 22 may be soldered into small holes on the ends of end members 20 and 21, or may be soldered to the outer surfaces of these members. I have found that resistance heating of the soldered joints by means of a pencil tip soldering member produces excellent results, being sure to maintain the pencil tip in good contact throughout the entire soldering period in order to prevent arcing and burning of end members 20 and 21. Because end members 20 and 21 often are proportioned to have specific microwave properties in a transmission line, it is important that they not be damaged in this or in subsequent steps.

Reference now will be made to FIG. 3 which is intended to represent the view seen through the eyepiece of a microscope that is positioned over the assembly fixture illustrated in FIG. 1. The eyepiece of a microscope is provided with a reticle comprised of four spaced-apart vertical lines 71, 72, 73 and 74. The microscope is adjusted so that the outermost vertical lines 71 and 72 are coincident with the adjacent ends of pin members 20 and 21. A masking material that is resistant to the electrolytic process then is applied to cover the ends of pin members 20 and 21 and also extends onto a portion of the outer ends of resistance wire 22 so as to form the protective cones 68 and 69. As a masking material I have used the material known as Asphaltum "B" varnish, obtained from the Sherwin-Williams Company. The limit to which resistance wire 22 is masked is determined by the innermost vertical lines 73 and 74 of the reticle. The masking cones 68 and 69 are necessary because the deplating or electrolytic etching process otherwise would remove the gold or other plating from end member 20 and 21 and also would attack the exposed based metals of end members 20 and 21. The length

of resistance wire 22 that remains unmasked desirably is shorter than the length of the Wollaston wire that finally is etched. As will be explained hereinafter, this feature allows for precise control of the etching and assures substantially complete removal of the silver coating from the central portion of the platinum core of the Wollaston wire. If the etching process were not confined by properly positioned masking cones 68 and 69, the silver coating would be removed from the Wollaston wire in a more or less uniform manner until the platinum core was almost completely exposed over its entire length, and this would result in an excessively over-etched and excessively high resistance barretter element.

In the next step of the assembly of the barretter, a droplet 34 of the electrolyte is placed within reservoir 33, and by means of the apparatus 30 of FIG. 1, is brought into contact with the unmasked central portion of resistance wire 22 so as to completely surround the unmasked portion in the manner illustrated in FIG. 2. The appropriate electrical connections then are made in accordance with the schematic diagram of FIG. 2 to insert the resistance wire 22 into one leg of the bridge circuit 81, and to establish the electrolytic etching current path that includes a source of D.C. potential E_{de} , positioning member 17, end member 21, resistance wire 22, droplet 34 of the electrolyte, reservoir 33, tool 31, and plating control circuit 83. With bridge circuit 81 proportioned to be in a balanced condition when resistance wire 22 has been electrolytically etched to its desired resistance value, the bridge initially will be in an unbalanced condition since the resistance of the unetched Wollaston wire is relatively low. In this unbalanced condition of bridge circuit 81, amplifier 60 will be energized by an unbalanced A.C. signal from bridge circuit 81 and will provide a signal to etching control circuit 83 which in turn operates to close the electrolytic etching current conducton path, thus permitting the electrolytic etching process to commence. The electrolytic etching process will proceed relatively rapidly until the silver coating is substantially removed from the unmasked central portion of Wollaston wire 22. In this condition, the resistance of Wollaston wire 22 still is lower than its desired final value so that bridge circuit 81 still is in an unbalanced condition and the electrolytic etching current path still is maintained closed by the etching control circuit 83. The electrolytic etching process now proceeds at a slower rate by removal of the ends of the silver coating that lie under the protective cones 68 and 69. During this period of time the electrolytic etching continues on the exposed platinum wire so as to thoroughly "clean up" the last vestige of silver that remains after the early and rapid removal of the silver coating from the unmasked portion of Wollaston wire 22. It may be seen that this feature of the etching process will permit substantially complete removal of all silver particles from the exposed portion of Wollaston wire 22 and results in a superior etched wire whose characteristics will not substantially change with use. The etching process then proceeds slowly on the ends of the silver coating under the masking cones 68 and 69 until the desired resistance value is obtained. When this resistance value is achieved, bridge circuit 81 will be in a balanced condition and the output of amplifier 60 will be substantially zero. In the absence of an input to etching circuit 83 from amplifier 60, etching control circuit 83 operates to open the electrolytic plating current path and thus terminate the electrolytic etching process. It thus may be seen that the electrical control circuitry illustrated in FIG. 2 provides means for stopping the electrolytic etching process at the precise moment that the desired value of resistance has been obtained, and inasmuch as a chemical etching solution is not employed, no further etching action will take place. It may be seen that the manufacture of barretters by the method of this invention may be carried out by relatively unskilled personnel inasmuch as the automatic

control of the etching process completely eliminates the requirement that the operator rely upon his judgment to determine when the etching process should be terminated. If desired, an indicating light may be added to etching control circuit 83 to indicate when the etching process has been completed. Further, the use of the electrolytic etching process and the protective cones 68 and 69 produces an etched wire of superior quality having substantially no particles of silver remaining on the etched portion, and these superior results are constantly repeatable due to the automatic control of the etching process. A further advantageous feature of this invention is that an operator may attend more than one assembly fixture at the same time since his attention is not required once the etching process has commenced.

At the conclusion of the etching or deplating process just described, the droplet of electrolyte 34 is withdrawn from contact with the etched wire 22. Because of the very delicate nature of the etched wire, extreme care must be used in order that the surface tension of the droplet 34 with the wire does not cause the wire to break as the droplet is withdrawn. In order to reduce the surface tension, a suitable wetting agent may be mixed with the electrolyte to reduce its surface tension. The operator then proceeds with the assembly of the barretter by cleaning the etched resistance wire to remove the electrolyte, any loose metallic particles, and the protective cones 68 and 69. This may be accomplished by inserting a portion of the assembly fixture of FIG. 1 into an ultrasonic cleaning tank, and then rinsing with grain alcohol. Following the cleansing operation, set screw 28 is partially backed off and shim 62 is withdrawn from the fixture. Conductive positioning member 16 then is carefully pushed inwardly until shoulder 18 abuts against the outer surface of end member 11. Set screw 28 then is tightened to secure positioning member 16. This causes a slight bend to form in the etched portion of the Wollaston wire 22, see FIG. 4, thereby relieving any tension on the wire and rendering it less susceptible to breakage due to shock and vibration. The resistance of the etched wire 22 again may be checked to make sure that it meets the desired requirements and, if acceptable, the encapsulating sleeve 65 of FIG. 1 is moved to the right so that its two ends engage the respective closing plug portions 24 and 25 on end members 20 and 21. Encapsulating sleeve 65 then is secured to closing plugs 24 and 25 by any suitable means such as an adhesive.

While the invention has been described in its preferred embodiments it is to be understood that the words which have been used are words of description rather than of limitation and that changes within the purview of the appended claims may be made without departing from the true scope and spirit of the invention in its broader aspects.

What is claimed is:

1. Apparatus for use in electrolytically etching a power absorbing resistance wire comprising,
means for supporting two conductive members in spaced apart relationship,
means for supporting an electrolyte in a region between said conductive members,
means connected to said spaced conductive members comprising the arms of known resistance values of a resistance measuring bridge circuit,
means for connecting a source of direct current between one of said spaced conductors and said electrolyte supporting means, and
means responsive to an output signal of said bridge circuit to disconnect said direct current source only when said output signal is of a predetermined value.
2. Apparatus for use in electrolytically etching a power absorbing resistance wiring comprising,
means for supporting two conductive members in spaced apart relationship,

said conductive members being adapted to have a length of power absorbing resistance wire extended therebetween,
 an electrode disposed in a region between said conductive members,
 circuit means connected between said conductive members comprising the arms of known resistance values of a resistance measuring bridge circuit,
 said conductive members comprising terminals of the arm of unknown resistance value of said bridge circuit,
 a source of direct current etching current connected between one of said spaced conductors and said electrode, and
 means operable in response to a condition of balance of said bridge circuit to disconnect said direct current source when said bridge circuit is in a condition of balance.

3. The combination claimed in claim 2 and further including,
 an alternating current signal source for energizing said bridge circuit.

4. The combination claimed in claim 3 and further including direct current isolating means coupled between said bridge circuit and said direct current disconnect means.

5. Apparatus for use in electrolytically etching a power absorbing resistance wire comprising,
 means for supporting two conductive members in spaced apart relationship,
 an electrode disposed between said spaced conductive members for use in making electrical contact with an electrolyte to be used in electrolytically etching said wire,
 means connected to said spaced conductive members comprising the arms of known resistance values of a resistance measuring bridge circuit,
 said conductive members comprising terminals of the arm of unknown resistance value of said bridge circuit,
 means for connecting a source of direct current etching current between said electrode and one of said conductive members, and
 means operable in response to an output signal of said bridge circuit to disconnect said direct current source when said output signal is of a predetermined magnitude.

6. Apparatus for use in electrolytically etching a power absorbing resistance wire comprising,
 means for supporting two spaced apart conductors,
 means for supporting an electrolyte in a region between said conductors,
 means connected to said spaced conductors comprising the arms of known resistance values of a resistance measuring bridge circuit,
 said conductors comprising terminals of the arm of unknown resistance value of said bridge circuit,
 means for connecting a source of direct current between one of said spaced conductors and said electrolyte supporting means, and
 means operable in response to a condition of balance of said bridge circuit to disconnect said direct cur-

rent source when said bridge circuit is in a condition of balance.

7. Apparatus for use in electrolytically etching a power absorbing resistance wire comprising,
 means for supporting two conductive members in spaced apart relationship,
 said conductive members being adapted to support therebetween a length of resistance wire to be electrolytically etched,
 an electrode disposed between said spaced conductive members for use in making an electrical contact with an electrolyte to be used in electrolytically etching said wire,
 means for connecting a source of direct current etching current between said electrode and one of said conductive members,
 resistance measuring means connected to said spaced conductive members for use in determining the resistance value of a wire extended between said conductive members,
 an alternating current source coupled to said resistance measuring means,
 whereby resistance measurements are made in response to alternating current signals that energize said resistance measuring means,
 direct current disconnect means included in said means for connecting a source of direct current between said electrode and one of said conductive members, said disconnect means operating to interrupt the direct current when the resistance measuring means produces a given output signal, and
 direct current isolating means connected between said resistance measuring means and said disconnect means.

8. Apparatus for electrolytically etching a Wollaston wire comprising,
 means for supporting first and second conductive members in spaced apart relationship,
 a liquid reservoir disposed between said supporting means,
 circuit means comprising the arms of known resistance values of a resistance measuring bridge circuit,
 means for electrically connecting said circuit means to said spaced conductive members so that a length of Wollaston wire connected between said spaced conductive members would comprise the known resistance arm of said bridge circuit,
 a source of direct current for supplying an etching current to etch a length of Wollaston wire supported between said conductive members,
 means for coupling said direct current source to said reservoir and to one of said conductive members, and
 means operable in response to a condition of balance of said bridge circuit for disconnecting said direct current source when said bridge circuit is in a condition of balance.
